UNITED STATES PATENT OFFICE.

RAYMOND D. FOLTZ, OF EAST ORANGE, NEW JERSEY, ASSIGNOR TO M. H. DETRICK COMPANY, OF CHICAGO, ILLINOIS, A CORPORATION OF ILLINOIS.

FURNACE CONSTRUCTION.

Application filed August 23, 1923. Serial No. 658,898.

To all whom it may concern:

Be it known that I, RAYMOND D. FOLTZ, a citizen of the United States, residing at East Orange, in the county of Essex and State of New Jersey, have invented certain new and useful Improvements in Furnace Constructions, of which the following is a specification.

This invention relates to furnace construction, and pertains to improvements in the construction of the portions commonly known as the furnace arch and an associated apron wall or curtain wall.

The general purpose of the invention is the provision of a construction which will be effective to maintain the desired relationship of an apron or curtain wall with an arch of the flat or suspended type and with the associated portions of the installation, such as boiler parts. It frequently occurs that it is desirable to provide an apron or curtain wall in association with the terminus of an arch portion of a furnace in such relationship that the wall provides an upward continuation of the refractory closure or surface afforded by the arch, whence it results that the continuity or integrity of the closure requires the maintenance of those parts in such fashion that they will not be forced out of position by the expansion and contraction of the structure incident to changes in temperature. In the use of so-called flat arches, or suspended arches, in which the refractories are hung from supporting members disposed above a furnace chamber, the proper support of the curtain or apron wall portions presents certain difficulties, due to the fact that its lower limit must conform to the shape of the rear end of the arch and it must be supported across the entire width of the furnace chamber. Provision has been made heretofore for carrying the apron or curtain wall upon the terminal portion of the arch or upon metallic brackets associated therewith and arranged in such disposal as to be covered inwardly by the refractories included in the arch and wall portions. When so supported, it sometimes occurs that incident to the effects of the furnace temperatures, the portions of the apron or curtain wall will be warped or sprung inwardly, sometimes to a degree which will cause portions of the wall to overturn. In other instances portions of the wall may be

displaced to such an extent that they contact adjacent boiler parts, a condition which is likely to result in serious injury thereto. In some instances this displacement of the curtain or apron wall portions by the temperature influences is facilitated by the circumstance that the bottom refractories in the wall do not bond with metallic bracket portions upon which they are supported, and by the fact that the bonding area between those refractories and juxtaposed refractories in the arch is limited by the interposition of the metallic members. By means of the present improvements I am enabled to obviate these difficulties and provide for the maintenance of the apron or curtain wall securely in proper position, so that it may exercise properly its intended function as a part of the furnace closure and as an instrumentality for properly directing and distributing the furnace heat and products of combustion.

For the purpose of this application I have elected to present one form in which the invention may be embodied, but it is to be understood that the same is here presented for the purpose of illustration only, and that it is not to be accorded any interpretation having the effect of limiting the invention which I purport to secure, short of its true and most comprehensive scope in the art. In the drawing forming a part of this specification, in which said embodiment is shown,

Fig. 1 is a part sectional elevation of a terminal portion of a furnace arch shown in relationship to associated boiler parts and curtain wall;

Fig. 2 is a part horizontal section of the structure, on which the section illustrated in Fig. 1 is taken substantially on the line 1-1;

Fig. 3 is a refractory tile of conventional form suitable for use in an assembly embodying my invention; while

Figs. 4 and 5 are perspective views of metallic brackets or supporting members designed for use in the structure.

The nature of the invention will best be ascertained by reference to these drawings in detail, whence it will be understood that the reference character 1 designates lateral wall portions of a furnace chamber designed to afford a combustion space in association with a boiler, here illustrated as of a vertical type and including water tubes 2 seated in a

header 4. As parts of the flat or suspended arch structure, forming an upper portion of the combustion chamber, are beams 5 supported above the chamber and affording carrying members for the tile supporting members 6. Upon the latter are suspended refractory tile 7, of conventional form, in such relationship as to form part of the furnace arch. At the terminus of the arch, as where the combustion chamber connects with the boiler passes, or where the refractory arch surface changes direction toward the vertical, are suspended wedge shaped tile 8 to provide a continuation of the refractory surface around a bend or an arch nose. In association with this portion of the arch is supported a bracket 9 having a wall supporting shelf 9^a extending above the uppermost wedge shaped tile, any space intervening between those tile and the shelf being filled with refractories 10 laid upon the topmost of the tile 8. Forms which the bracket 9 may take are illustrated in Figs. 4 and 5, these forms being adapted for support on the tile supporting members 6. The shelf portion 9^a presents a flat upper surface adapted to function as a support for a tile laid flat thereupon, but the shelf is of substantially smaller area than a tile of the width of the courses supported on the tile supporting members 6. A plurality of the brackets 9 are arranged in collateral disposal at the marginal portion of the arch and preferably in alignment with the courses of tile carried on the tile supporting members. At the forward portion of the shelf 9^a the bracket is provided with an upstanding lug or flange 9^b of proper width to engage in the suspension slot of a tile 7', such as that illustrated in Fig. 3, when the tile is laid upon the shelf portion 9^a. The height of the tile retaining lug 9^b may be of sufficient to engage only one of such tile, or it may be of sufficient height to engage in the slots of a plurality of such tile when superimposed, as with the form illustrated in Fig. 5. Forwardly from the tile retaining lug 9^b the bracket advantageously may be formed with a horizontal flange 9^c of sufficient width to engage the lateral faces of the suspension shoulders 7^a of the tile. By virtue of this arrangement of parts the tile supported on the shelf portion 9^a is retained thereon against movement in any horizontal direction sufficient to permit dislodgment of the tile. However, the tile retaining lug has sufficient play in the slot of the tile to accommodate the usual amount of expansion in those members. With the tile thus supported, their lateral margins are maintained in alignment with the lateral margins of tile carried on the tile supporting members 6, so that they may be regarded as lying in the same longitudinal courses. As will be observed in Fig. 2, the tile overlaps all margins

of the shelf, and the space intervening between the tile and the subjacent refractories 10 is grouted with fire clay, ganister, or other suitable refractory material such as will effectively seal the shelf portion from the interior of the furnace. The tile thus supported on the shelf portions of the brackets, and there retained, by the tile restraining lugs, constitutes the bottom course of the apron or curtain wall which may be built upwardly upon them out of ordinary fire brick 11, bond between the bottom tile and those thereabove being secured in the customary fashion. The apron or curtain wall may take the form appropriate to its particular location and function, and it will be seen that it constitutes an upward continuation of the refractory surface afforded by the tile 7 and 8.

It will be observed that by virtue of this construction fixed anchorage is afforded for the entire curtain wall in proper association with the terminus of the arch and with associated portions of the installation, as the engagement of the foundation tile with the tile retaining lugs positively prevents their being displaced, irrespective of the limited bond obtainable between those tile and the shelf portions 9^a or the refractories 10, and this anchorage of the foundation tile is effective to hold the superimposed refractories 11 in position by virtue of the bond between them. Thus, not only is the integrity of the closure maintained, but the curtain wall portions are retained in the desired relationship to distribute and direct the furnace gases properly with respect to the boiler tubes. Moreover, the refractories in the curtain or baffle wall are thus securely maintained against overturning or creeping into contact with the boiler tubes, a contingency likely to result in serious consequences. One feature of advantage resides in the fact that the construction requires no additional special form of refractories, as tile of the sort customarily employed in the arch construction are suitable for use as the foundation tile. A further advantage in the construction lies in the fact that it affords means for sustaining an apron or baffle wall portion in a more or less sloping position after the fashion of the arrangement illustrated in Fig. 5, while in all embodiments it facilitates the closing off of the supporting bracket from the interior of the furnace in such fashion as to give it full protection from the heat. The portions of the bracket projecting at the exterior of the structure function effectively to radiate heat from the parts enclosed by the refractory members.

Certain features of construction herein disclosed are claimed in a co-pending application of Louis H. Hosbein, Serial No. 650,991, filed July 12, 1923.

What I claim is:

1. In furnace construction, the combination with an arch portion, of brackets supported in association therewith, said brackets being provided with shelf portions and tile retaining lugs, tile supported in horizontal position by the shelf portions and engaging the lugs, and refractories supported on said tile to form in conjunction therewith a wall portion associated with the arch portion. 65
2. In furnace construction, the combination with an arch portion, of brackets supported in association therewith, said brackets being provided with shelf portions and tile engaging lugs, and slotted tile supported on the shelf portions and engaging said lugs, whereby said tile are retained against shifting off of the shelf portions. 70
3. In furnace construction, the combination with tile disposed in courses to form an arch portion, of brackets associated with the arch portion, said brackets having shelf portions and tile retaining lugs, and tile supported on said shelf portions and retained by said lugs in alignment with the courses in the arch portion. 75
4. In furnace construction, the combination with an arch portion, of collaterally arranged brackets supported in association therewith, said brackets having shelf portions and tile retaining lugs, and tile supported on the shelf portions above the arch portion and retained against dislodgment by said lugs. 80
5. In furnace construction, the combination with refractories suspended to provide an arch portion, of brackets associated with said arch portion, said brackets having shelf portions and tile retaining lugs, tile supported on said shelf portions and engaging said lugs, whereby they are retained against displacement, and refractories laid upon said tile to form an apron wall portion as a continuation of the arch portion. 85
6. In furnace construction, the combination with beams arranged above the furnace chamber, of tile supporting members suspended from said beams, tile suspended on said tile supporting members to form an arch portion, brackets supported on the tile supporting members, said brackets having shelf portions and tile retaining lugs, and tile supported on the shelf portions and engaging said lugs, whereby said tile are retained against displacement from the shelf portions. 90
7. In furnace construction, the combination of tile supporting members suspended above the furnace chamber, refractories suspended on said tile supporting members to form an arch portion, brackets supported on said tile supporting members at the terminus of the arch portion, said brackets having shelf portions and tile retaining lugs, and tile resting on said shelf portions and engaging said lugs, whereby said tile are retained in alignment with refractories in the arch portion. 95
8. In furnace construction, the combination with tile supporting members, of refractories suspended thereon to form an arch portion, brackets supported in association with the terminus of said arch portion, said brackets having shelf portions and tile retaining lugs, and tile supported on said shelf portions with the lateral sides of juxtaposed tile in contact, said tile engaging said lugs, whereby said tile are retained against relative displacement. 100
9. In furnace construction, the combination of brackets supported above the furnace chamber, refractories supported in association with said brackets to form a refractory arch portion between them and the furnace chamber, said brackets having shelf portions and tile retaining lugs, tile disposed on said shelf portions and engaging said lugs, and a curtain wall portion built upon said tile. 105
10. In furnace construction, the combination of brackets supported above the furnace chamber, refractories suspended therefrom to form an arch nose, said brackets having shelf portions and tile retaining lugs, tile supported on said brackets and engaging said lugs, whereby said tile are retained against dislodgment, and an apron wall portion built upon said tile. 110
11. In furnace construction the combination of brackets collaterally arranged above the furnace chamber, said brackets having shelf portions projecting at one side and attaching portions projecting at the other side whereby they are supported, and tile retaining portions extending above the shelf portions, and slotted tile supported on the shelf portions and engaging the tile retaining portions, whereby the tile are retained against displacement with respect to the brackets. 115
12. In furnace construction, in combination, brackets pendulously suspended above the furnace chamber, refractories pendently supported thereon to form a refractory arch portion below the brackets, said brackets having shelf portions projecting over some of the suspended refractories and tile retaining portions extending above said shelf portions, slotted tile lying upon said shelf portions and engaging said retaining portions, and refractories laid on said tile to form an apron wall portion extending upwardly from the arch. 120
- In testimony whereof I have hereunto subscribed my name. 125

RAYMOND D. FOLTZ.
